VALVE-ACTUATING MECHANISM

Anthony F. Buzas, Philadelphia, Pa.

Application May 13, 1952, Serial No. 287,571

3 Claims. (Cl. 249—58)

1

The present invention relates generally to scale-actuated valve-operating mechanism and more particularly to scale-actuated quick-acting valve-closing means.

An object of the present invention is to provide a novel scale-actuated valve-operating mechanism. Another object of the present invention is to provide a simple, inexpensive, yet dependable device for quickly operating a valve or the like responsive to movement of a balance or scale or the like.

Other objects and advantages of the present invention are apparent in the following detailed description, appended claims and accompanying drawings.

For the purpose of illustrating the invention, there are shown in the accompanying drawings forms thereof which are presently preferred; it being understood, however, that the invention is not limited to the precise arrangements and instrumentalities shown, and that the several parts and elements can be variously arranged and organized without departing from the spirit and essential attributes of the invention.

Referring to the drawings, in which like reference characters indicate like parts throughout:

Figure 1 is a side elevational view of one embodiment of the present invention.

Figure 2 is an enlarged cross-sectional view taken generally along the line 2—2 of Fig. 1.

Figure 3 is a further enlarged vertical cross-sectional view showing the catch and release mechanism in locked valve-open position.

Figure 4 is a view like that of Fig. 3 but showing the mechanism in released valve-closed position.

Figure 5 is a view like that of Fig. 3 but showing another embodiment of the present invention.

Figure 6 is a view, partly in vertical cross-section and partly in side elevation, showing still another embodiment of the present invention.

Figure 7 is a side elevational view of a further embodiment of the present invention.

Figure 8 is a vertical cross-sectional view taken generally along the line 8—8 of Fig. 7.

Figure 9 is a fragmentary side elevational view showing a modified form of the embodiment of Fig. 7.

In Figs. 1-4, I have shown one embodiment of the present invention constructed and arranged to close a valve immediately after a predetermined weight of liquid or paste or powder has been delivered to a container C positioned on a weighing-platform P' of a conventional balance-type scale S having weights W on its other platform P''.

In this embodiment, the flow of liquid or like material through a generally vertical delivery

2

pipe 20 is controlled by a gate valve 21 of generally conventional construction, operatively connected within the pipe 20 and having a valve-disc 22 which can be moved to either open position (shown in solid lines in Fig. 2) or closed position (shown in dash-dot lines in Fig. 2) upon axial movement of a valve stem 23.

The valve stem 23 is provided with a bifurcated free end 24, through which extends an operating handle 25 and about which is positioned the yoke portion 26 of a sliding brace 27 to be hereinafter described. About the yoke portion 26 in turn is positioned the bifurcated end 28 of an arm 29 which extends in axial extension of the valve stem 23 and which will be more fully described below.

A link-pin 30 extends through aligned openings in the bifurcated end 28, the yoke portion 26, the bifurcated free end 24, and the operating handle 25; locking them together while permitting pivoting of the operating handle.

One end 31 of the operating handle 25 is pivotally connected, as at 32, to an end of a slide-bar 33 which extends through an appropriate opening in the sliding brace 27 and is fastened at its other end to a lug 34 formed on the housing of the valve 21, by means of a pin 35. The brace 27 is slidable along the slide-bar 33 and is tensioned to the dash-dot line position of Fig. 2 by a helical spring 36 which is connected at one end to the pin 35 and at the other end to a screw 37 mounted on the brace 27.

In this last-mentioned position, the valve 21 is closed. However, when the handle 25 is manually shifted from the dash-dot line position of Fig. 3 to the solid-line position (pivoting clockwise about the pin 32 connecting it to the slide-bar 33), the brace 27, the extension arm 29, the valve-stem 23 and the valve-element 22 are moved, against the pull of the spring 36, toward the left in Fig. 2, so as to open the valve and to permit the flow of fluid through the pipe 20.

The extension arm 29 (the cross-sectional configuration of which is preferably non-circular, as for example rectangular) is provided with a locking-notch 39 on its underside and extends slidably through a horizontal opening 40 formed adjacent the upper end of a housing 41, which is suspended, by a bolt 42, from the upper horizontal arm of an L-shaped structural member 43, which is bolted to, and extends upwardly from, the base E of the scale S.

The housing 41 is also provided with a generally vertical opening 44 extending downwardly from the midpoint of the horizontal opening 40 to the upper end of a cut-out portion 45, and with a

second vertical opening 46, co-axial with the opening 44 and extending downward from the lower end of the cut-out portion 45 to the bottom of the housing.

Extending through the cut-out portion 45 and 5 slidably mounted within the openings 44 and 46 is an elongated locking-member 47 (the cross-sectional configuration of which is preferably non-circular, as for example rectangular) provided with a collar 48 disposed within the cut-out portion 45; a helical compression spring 49 being fitted about the locking-member and being constructed and arranged to bear against the under-side of the collar 48 so as normally to urge the locking-member upwardly, whereby the pointed upper end 50 of the locking-member 47 is locked within the locking-notch 39 of the extension arm 29, when the latter is in the extended position shown in solid lines in Fig. 2 and also shown in Figs. 1 and 3.

Extending downward from the lowermost protruding end 51 of the locking-member 47 is a chain 52, which is secured, at its lower end, to a rod 53 extending generally horizontally from the weighing-platform P' of the scale S. The length of the chain 52 is such that it permits full upward movement of the locking-member 47, into locking engagement with the extension arm 29 when the beam A of the scale S is in the clockwise tilted position shown in solid lines in Fig. 1; i. e. when the moment of rotation of the container C and its contents resting on weighing-platform P' is less than the moment of rotation of the weights W resting on weighing-platform P''. However, when the moment of rotation of the container and its contents exceeds that of the weights so that the beam A tilts counterclockwise to the position shown in dash-dot lines in Fig. 1, the downward movement of the platform P', the rod 53 and the chain 52 causes the locking-member 47 to be pulled downward (against the force of its spring 49) until its upper end 50 is disengaged from the locking-notch 39, thereby permitting the extension arm 29 to move toward the right (under the pull of the spring 36), as shown in Fig. 4 and also shown in dash-dot lines in Fig. 2.

The operation of this embodiment is as follows: The weights W, corresponding to the total weight of the container C and its contents, are first placed upon the weighing-platform P'' and the empty container C is placed upon the other weighing-platform P'; the beam A tilting to the solid-line position of Fig. 1. The operating handle 25 is then manually shifted from the dash-dot line position of Fig. 1 to the solid-line position, thereby opening the valve and moving the extension arm 29 from the position of Fig. 4 to the position of Fig. 3, wherein the locking-notch 39 is in line with, and is automatically engaged by, the upper end 50 of the locking-member 47, thereby locking the valve 24 in open position and permitting fluid or the like to flow downward through the pipe 28 and into the container C.

As soon as the container is filled to the point at which its total weight exceeds the predetermined figure required to exceed the moment of rotation of the weights on weighing-platform P'', the beam A tilts counterclockwise from the solid-line position of Fig. 1 to the dash-dot-line position, the locking-member is pulled downward against the pressure of its spring 49 to release the extension arm 29 and to permit the valve to close under the pull of the spring 36, as described above; thereby stopping the flow of fluid or the like to the container.

By making a suitable allowance for the relatively slight force needed to overcome the push of the spring 49, it is possible to obtain extremely accurate deliveries of predetermined amounts of fluid or the like to the container. The fact that the locking-member 47 must be moved downward only a very short distance in order to release the extension arm 29, plus the fact that the relatively strong pull of the spring 36 gives a swift, positive closing movement of the valve-element 22, means that the valve is closed with a sudden snap action which is completed even before the scale beam reaches its fully-tilted position, shown in dash-dot lines in Fig. 1. Of course, if there is any considerable length of pipe below the valve, a further allowance can be made for the amount of fluid or the like remaining therein, which will flow into the container after the valve is closed. Obviously, it is a simple matter to determine this last-mentioned weight and to make a corresponding correction in the weights on the platform P''.

The filled container is removed from the scale and replaced by an empty container of the same weight (or the same container may be emptied and replaced) and the handle 25 is again manually shifted from the dash-dot line position of Fig. 2 to the solid-line position to repeat the filling cycle.

In Fig. 5, there is shown a slightly modified embodiment in which the locking-notch 39-a of the extension arm 29-a and the upper end 50-a of the locking-member 47-a are generally rectangular in configuration (instead of being tapered as in Figs. 3 and 4); the locked-open valve position being shown in solid lines and the released valve-closed position being shown in dash-dot lines. This modification may be preferred in the case of large valves which require very strong springs 36, such as might exert sufficient pull to cause inadvertent camming displacement of the tapered upper end 47 of Figs. 3 and 4 and thereby result in premature shutting off of the valve.

In Fig. 6, there is shown another modification in which the locking-notch 39-b of the extension arm 29-b is generally arcuate in configuration and in which the locking-member 47-b is generally circular in cross-section, with a rounded upper end 50-b adapted to fit within the arcuate notch 39-b. In this embodiment, the extension arm 29-b and the valve-stem 23 are disposed at an angle (as for example 45 degrees), instead of being horizontal, as in the embodiment of Fig. 1; while the valve assembly is turned so that the direction of fluid flow through the valve is generally horizontal, while the operating handle 25 extends generally vertically upward (as compared to vertical fluid-flow and a horizontally-extending operating handle in the embodiment of Figs. 1-4). This embodiment has the advantage of conserving space since it enables the housing to be positioned closer, horizontally, to the valve and hence permits the device to be used in relatively close quarters. In this embodiment, the free end of the pipe may, optionally, be provided with a down-spout 32 to permit direct filling into an open-top container positioned on a scale as in the embodiment of Fig. 1.

In Figs. 7 and 8, there is shown another embodiment of the present invention adapted for use with a somewhat different type of gate valve 100, installed within a horizontal pipe line 101 having a downspout 102 adapted to deliver liquid or paste or powder to an open-top container C positioned on a weighing-platform P' of a con-

ventional balance-type scale S having a beam A mounted on a fulcrum F , with weights W disposed on its other platform P' .

As indicated in Fig. 8, the valve 100 includes a valve-disc 103 adapted to be opened and closed upon pivotal movement of an operating handle 104 ; the valve being closed when the handle is in the lowered counterclockwise-rotated position shown in dash-dot lines in Fig. 8, and being opened when the handle is in the raised clockwise-rotated position shown in solid lines.

Mounted on the handle 104 is an upwardly-directed apertured locking-block 105 , which is adapted to be brought into generally horizontal alignment with a locking-rod 106 when the handle 104 is in the raised clockwise-rotated valve-open position shown in solid lines in Fig. 8. The locking-rod 106 is slidably supported by a pair of apertured blocks 107 and 108 , suspended from the ceiling in any suitable manner, and is provided with a collar 109 disposed intermediate the blocks. A helical compression spring 110 is mounted on the locking-rod intermediate the block 107 and the collar 109 and exerts force upon the collar tending to move the locking-rod (toward the right in Fig. 7) so that its end enters the apertured locking-block 105 when the handle 104 is in the raised position shown in Fig. 7 and also shown in solid lines in Fig. 8, thereby locking the valve 100 in open position. It is apparent that, when the locking-rod 106 is withdrawn (i. e., moved toward the left in Fig. 7), the handle 104 is released and is free to fall, of its own weight, to the valve-closed position; a C-shaped stop 111 , suspended from the ceiling, serving to limit the downward movement of the handle and to relieve the valve mechanism of the shock of fall.

To the other end of the locking-rod 106 is connected a chain 112 which extends generally horizontally therefrom, across a sheave 113 , suspended from the ceiling, and downward to a rigid rod 114 extending generally horizontally from the weighing-platform P' . The length of the chain 112 is such that, when the container C is empty and the beam is in the clockwise-rotated position shown in solid lines in Fig. 7, the locking-rod 106 is free to extend within the apertured locking-block 105 . However, when the container is filled to a point at which it overbalances the weights and causes the beam to swing to the counterclockwise-rotated position shown in dash-dot lines in Fig. 7, downward movement of the weighing-platform P' and the rod 114 causes the chain 112 to pull the locking-rod 106 (to the left in Fig. 7) against the pressure of its spring 110 , until its end clears the apertured locking-block and permits the handle 104 to fall to valve-closing position, as described.

The locking-block 105 is provided with an inclined camming edge 115 which causes momentary retraction of the locking end of the locking-rod 106 when the handle is manually raised from the counterclockwise-rotated valve-closed position to the clockwise-rotated position, after which the locking-rod is re-extended by its spring when the locking-block aperture comes into alignment with it, thereby automatically locking the handle in elevated valve-open position.

It is apparent from the foregoing that, with an empty container on the weighing-platform P' , it is only necessary to lift the handle 104 so as to open the valve 100 and to permit flow of fluid

or the like into the container. As soon as the container has been filled to the predetermined weight, counter-clockwise rotation of the balance beam will cause the chain to shift the locking-rod, releasing the handle which drops, shutting off the valve quickly and effectively and with a high degree of accuracy.

The filled can is then removed from the scale and replaced by an empty can of the same weight (or is itself emptied and replaced), and the handle 104 manually raised and automatically locked in valve-open position to begin a new filling cycle.

It is apparent that, instead of relying on the force of gravity to move the released operating handle to valve-closing position, it is possible to provide a spring or weights or other conventional means for producing this movement.

Appropriate compensation may be made, in the weights, to allow for the force needed to overcome the force of the spring 110 where a high degree of accuracy in weighing is desired.

In Fig. 9, there is shown a somewhat modified embodiment in which the sheave is replaced by a bell-crank 116 pivotally supported from the ceiling by a bracket 117 and having a short, generally upwardly-directed arm 118 and a relatively longer generally horizontally-directed arm 119 . A chain $112-a$ extends generally horizontally from the end of the shorter arm 118 to the locking-rod 106 , while another chain $112-b$ extends downward from the end of the longer arm 119 to the rod 114 .

It can readily be seen that downward movement of the weighing-platform P' , the rod 114 and the chain $112-b$, in the manner described above, will cause counterclockwise tilting of the bellcrank and will result in movement of the chain $112-a$ and the locking-rod 106 toward the left so as to disengage and release the operating handle for valve-closing falling movement thereof.

While the bell-crank thus acts as the mechanical equivalent of the sheave of Fig. 7 in converting vertical movement to horizontal movement, it also serves to increase sensitivity by reducing the pull needed to overcome the pressure of the spring and to shift the operating-handle to valve-closing position; the mechanical advantage afforded by the unequal bell-crank arms reducing the force needed for this, in obvious manner.

The foregoing embodiments are to be considered, in all respects, merely as illustrative and not restrictive and, therefore, reference should be made to the appended claims, rather than to the above description, as indicating the scope of this invention.

Having thus described my invention, I claim as new and desire to protect by Letters Patent:

1. For use with a quick-acting valve having an axially shiftable valve stem and being constructed and arranged to control the flow of fluid or the like through a pipe line and into a container positioned upon the weighing-platform of a balance-beam type scale; mechanism for automatically cutting off the flow when a predetermined amount has been delivered to the container comprising a pivotally mounted operating handle hingedly connected to the end of the valve stem, said handle being provided with spring means normally tensioning it to valve closing position and being manually shiftable to valve opening position, a notched rod connected to the end of said valve stem and movable therewith in axial extension thereof, a movable locking-member

normally spring-urged into position wherein it engages said extension rod and cooperates with the notch to lock the rod, the handle and the valve stem in valve open position, and means connecting said locking member with the weighing-platform whereby downward movement of the platform will shift the locking-member to position freeing the extension rod and permitting spring-urged snap-action valve closing movement of the handle and the valve stem.

2. A construction according to claim 1 wherein the locking-member is slidably mounted to move perpendicularly to the axis of movement of the extension rod.

3. A construction according to claim 1 wherein the locking-member is slidably mounted to move at an angle to the axis of the extension rod

and to form an acute angle therewith when connected thereto.
